GARMENT SUPPORTING ATTACHMENT FOR A CLOTHES HANGER

Richard E. Quadara, 12 McLean St., Passaic, N.J.

Filed June 9, 1964, Ser. No. 80,355

Term of patent 14 years

(Cl. D80—8)

FIG.—3—

FIG.—6—

FIG.—2—

FIG.—4—

FIG.—1—

FIG.—5—

FIG. 7-

FIGURE 1 is a top plan view of a garment supporting attachment for a clothes hanger showing my new design; FIGURE 2 is a side elevational view thereof;

FIGURE 3 is an end elevational view thereof, taken from the left side as viewed in FIGURE 2;

FIGURE 4 is a side elevational view corresponding to FIGURE 2 and wherein the flat channel member is longer and terminates in a bulbous end;

FIGURE 5 is an end elevational view thereof, taken from the left side as viewed in FIGURE 4;

FIGURE 6 is an end elevational view thereof, taken from the right side as viewed in FIGURE 4; and

FIGURE 7 is an isometric view showing a portion of a wire clothes hanger having attached thereto a garment supporting attachment.

The dotted lines of FIGURE 7 are for illustrative purposes only.

I claim:

The ornamental design of a garment supporting attachment for a clothes hanger, as shown and described.
